G. W. BERRY.

APPARATUS FOR CONNECTING THE BODIES AND LIDS OF PRESED SHEET METAL RECEPTACLES.
APPLICATION FILED AUG. 11, 1916.

1,219,428.

Patented Mar. 20, 1917

INVENTOR:

G. W. BERRY.

By his Atty. John A. Heifer

UNITED STATES PATENT OFFICE.

GEORGE WILLIAM BERRY, OF ROSE BAY, NEAR SYDNEY, NEW SOUTH WALES, AUSTRALIA, ASSIGNOR TO THE WIRELESS HINGE MANUFACTURING COMPANY LIMITED, OF SYDNEY, NEW SOUTH WALES, AUSTRALIA.

APPARATUS FOR CONNECTING THE BODIES AND LIDS OF PRESSIONED SHEET-METAL RECEPACLES.

1,219,428.

Specification of Letters Patent. Patented Mar. 20, 1917.

Original application filed April 22, 1916, Serial No. 93,013. Divided and this application filed August 11, 1916. Serial No. 114,372.

To all whom it may concern:

Be it known that I, GEORGE WILLIAM BERRY, a subject of the King of Great Britain, residing in Rose Bay, near Sydney, in the State of New South Wales, Commonwealth of Australia, engineer, have invented new and useful Improvements in Apparatus for Connecting the Bodies and Lids of Pressed Sheet-Metal Receptacles, of which 10 the following is a specification.

This invention relates to an apparatus for connecting the bodies and lids of pressed sheet metal receptacles, such receptacles comprising a body portion formed with 15 bulbed tongues and a rimmed lid portion adapted to fit over the body portion with hinge pintles formed integrally upon the lid rim upon which pintles said bulbed tongues are closed by the apparatus to form 20 a wireless hinge joint uniting said body and lid, and is a division of my co-pending application filed April 22, 1916 and bearing the Serial No. 93,013.

The apparatus comprises simple and efficient means designed so that the bulbed tongues are closed over the pintles in such a way that the lids will be correctly hinged and open and close quite freely on the receptacle.

30 In order that the invention may be readily understood reference will now be had to the accompanying sheet of explanatory drawings, wherein—

Figure 1 is a view in perspective of the 35 back part of a body showing bulbed tongues formed thereon to receive the pintles of a lid.

Fig. 2 is a view in perspective of the back part of a lid showing the pintles 40 formed integrally thereon.

Fig. 3 is a view in perspective of a punch and die block employed in closing the bulbed tongues of the body over the pintles on the lid.

45 Fig. 4 is a view in perspective of the punch shown in Fig. 3 and viewed from the opposite side.

In Figs. 3 and 4 the punch is shown tilted over to expose its under face to facilitate 50 description thereof.

Fig. 5 is a view in sectional elevation of the punch and die block, a body and lid

being shown in position for engagement on the die block.

Fig. 6 is a view in sectional elevation of 55 the punch and die block, showing the punch down on the die block and the bulbed tongues on the body closed over the pintles of the lid.

Fig. 7 is a view in perspective showing a 60 lid and body as fitted together by the closing apparatus.

The back of the body 1 is formed with raised tongues having inwardly opening bulbs 2 formed thereon to receive pintles 65 3 formed on a depending portion 4 of a lid 5. The pintles 3 project laterally from the ends of the depending portion 4 and slots 6 are formed between the pintles and the back of the lid rim to accommodate the 70 ends of the bulbed tongues when the same are closed over the pintles.

The body 1 is then placed over the vertical side of the closing die block 7 and the lid 5 is placed on the opposite side of the 75 said die block inclining toward the back of the body, so that the pintles 3 come directly beneath the bulbs 2 on the tongues which are then closed over the pintles 3 by the downward movement of the compound 80 closing punch 8.

The punch 8 of the closing die is formed in two parts, one part 9 being fixed in the ram and the other part 10 being slidable against backing springs 11. The slide 10 85 normally projects below the fixed part 9, and as the punch descends the two parts 9 and 10 are brought to bear one on either side of the bulbous part of the raised tongues and close them over the pintles 3. 90

The contiguous lower corners of the two parts of the closing punch 5 are corner fluted as at 12 to permit of the punch coming hard home without injuring the bulbs 2 or the pintles 3. 95

The fixed part 9 of the closing punch is formed with depending projections 13 which are adapted to pass through the slots 6 on the lid stock. The faces of the depending projections 13 approximate in size to 100 the outer ends of the bulbed tongues, and bear upon the upper sides and rounded ends of the said bulbs.

The closing die block 7 is formed with a

central depression 14 to accommodate the depressed portion 15 on the back of the receptacle body, and in the face of the said die block at the ends of the depression 14 are recesses 16 shaped to receive the edges of the stock from which the pintles are formed.

The bulbs 2 when the tongues are closed, are sufficiently large to permit free pivotal movement of the pintles 3 when the lid is being opened and closed.

What I do claim is:—

An apparatus for hingedly connecting a rimmed lid having pintles formed integrally on one rim thereof to a receptacle body having bulbed tongues inclining outwardly comprising a die-block shaped on one side to accommodate the receptacle body in a

vertical position and shaped on the opposite side to support the lid at an angle to the receptacle body, a compound punch having a fixed and a movable operative part, said movable part depending below the fixed part and slidable against resilient members, a groove formed by cutting away the longitudinal contiguous corners of the fixed and movable parts, and projections approximating in size to one half of said bulbed tongues formed on the face of the fixed part of said compound punch.

In testimony whereof I affix my signature in presence of two witnesses.

GEORGE WILLIAM BERRY.
